MAGNETIC TOY

Thomas M. Shelton, Glendale, Calif.

Application July 13, 1953, Serial No. 25,906

Term of patent 14 years

(Cl. D34—15)

FIG. 1.

FIG. 2.

To all whom it may concern:

Be it known that I, Thomas M. Shelton, a citizen of the United States, residing at Glendale, State of California, have invented a new, original, and ornamental Design for a Magnetic Toy, of which the following is a specification, reference being had to the accompanying drawings forming a part hereof.

Fig. 1 is a side elevational view of a magnetic toy, showing my new design;

Fig. 2 is an end view thereof;

Fig. 3 is a perspective view thereof; and

Fig. 4 is a side elevational view thereof.

I claim:

The ornamental design for a magnetic toy, as shown.
